FINN SIMMONS, OF NEW YORK, N. Y., ASSIGNOR, BY MESNE ASSIGNMENTS, TO NUCLEUS FURNITURE COMPANY, OF CHICAGO, ILLINOIS, A CORPORATION OF ILLINOIS.

FOLDING CHAIR.

Application filed November 8, 1927. Serial No. 231,945.

This invention relates to folding furniture and has particular reference to an improvement in folding chairs.

One of the principal objects of the present invention is to provide a folding chair, the elements of which when folded nest compactly within each other so as to occupy a minimum amount of space for storage or transportation.

10 The invention further comprehends a folding chair, the elements of which are so correlated as to fold and nest within each other to produce an article of minimum length from a chair of maximum size when 15 set up.

More specifically the invention comprehends in a folding chair, a back frame element with which a seat and supporting legs are foldably connected in such a manner 20 as to lie wholly within the confines of the back frame element and which chair is so constructed as to offer maximum rigidity when in a set-up condition.

The invention further contemplates a seat 25 frame and seat structure, the construction of which elements is such as to greatly facilitate their assembly and this without employing additional securing means other than their interfitted relation.

30 The invention further resides in the provision of a novel leg structure and bracing means therefor, together with seat and back frames having connection respectively therewith.

35 The invention furthermore embodies the features of simplicity of construction, economy of production and efficiency of function.

With the above recited and other objects 40 in view, reference is had to the following description and accompanying drawings in which there is exhibited one example or embodiment of the invention, while the appended claims define the actual scope of the 45 invention.

In the drawings—

Figure 1 is a side view of a folding chair 50 constructed in accordance with the invention and illustrating the same in set-up condition;

Fig. 2 is a front view thereof;

Fig. 3 is a front view on an enlarged scale of the chair in folded condition;

Fig. 4 is a sectional view therethrough

taken approximately on the line 4—4 of 55 Fig. 3;

Fig. 5 is a fragmentary transverse sectional perspective view of the seat frame and seat;

Fig. 6 is a fragmentary longitudinal section view of the seat frame and seat;

Fig. 7 is a fragmentary enlarged perspective view of the chair supporting and bracing connection between the leg and back frame elements.

Referring to the drawings by characters of reference, the chair includes a back frame element 10 of substantially inverted U-shaped configuration of angle construction in cross-section, presenting rear inwardly 70 extending flanges 11 and side forwardly extending flanges 12. A seat frame 13 of U-shaped configuration and of cross-sectional angular construction having upper inwardly extending flanges 14 and depending side 75 flanges 15, is provided. The free rear ends of the depending side flanges 15 of the seat frame are disposed within the side flanges 12 of the back frame and pivotally connected by pivots 16 thereto, whereby the 80 seat frame is pivotally connected for upward folding movement to a nested position within the back frame 10. A pair of front and rear legs 17 and 18 are pivoted on aligned pivots 19 to the depending side flanges of 85 the seat frame 13 within the side flanges. The rear legs 18 are of greater length than the front legs 17 and are adapted when the chair is set up, to be disposed at a rearward and downward inclination. In order to 90 limit the rearward swinging movement of the rear legs 18, links 20 are pivotally connected at 21 to the rear legs and pivotally connected at the opposite ends on a transverse rod 22 extending between and anchored to the lower ends of the side flanges 12 of the back frame 10, the lower ends of the rear inwardly extending flanges 11 having keeper notches 23 within which the links 20 are seated. In order to brace and hold 100 the front legs 17 in position, a yoke 24 is fulcrumed on the cross rod 22 and has the free front edges of the side arms 25 pivotally attached at 26 to the front legs. The combined distance between the pivotal points 16 to 22 to 26 is equal to the combined distance between the pivotal points 16 to 19 to 26, so that when the seat frame 13

is swung upwardly, the same will nest within the back frame while the legs 17 and 18 together with the links 20 and yoke 24 will nest partially within the seat frame and within the confines of the back frame. It thus follows that the folded chair occupies only the amount of space required for the back frame 10. The legs 17 and 18 while illustrated as of angle construction in cross-section, need not necessarily be of this shape, but in practice the legs will be suitably braced by connecting cross braces 27 and 28. The seat frame 13 will preferably have the depending flange 15 formed with an integral upwardly bent extension 29 which extension will have a laterally inwardly bent terminal flange 30 spaced from and parallel to the upper inwardly extending flange 14. A seat composed of a base 31 having a covering layer 32 of leather or other suitable material between which a padding or cushioning substance 33 is arranged, is adapted to be inserted within the seat frame between the flanges 14 and 30 from the rear open end of the frame. The rear end of the seat will be provided with a U-shaped metallic clip 34, which is frictionally driven between the flanges 14 and 30 to hold the same in place, thereby eliminating the use of rivets, welding, or other additional fastening means. The back frame bight 35 may, if desired, have arranged therein a padded or upholstered cross element 36, and said back frame may be further reinforced at a point between its juncture with the seat and its upper end, with a cross strip 37. The lower ends of the legs may be provided with suitable feet 38, if desired.

In order to provide means for locking the chair in an opened condition and to prevent any possibility of collapsing thereof, a latch in the form of a yoke or bail 39 is employed, the legs 40 of which are offset intermediate their length to provide locking shoulders 41. The free terminals of the legs are bent outwardly to provide trunnions 42 which are journaled in bearings 43 carried by the upper cross brace 28 of the legs 18. When in opened condition the bail gravitates downwardly until the shoulders 41 engage behind the upper cross brace 27 of the front legs 17. In this position, the bight 44 of the bail is disposed in convenient relation to the front edge of the seat frame so that in folding the chair the bail is grasped and moved upwardly by the same hand which moves the seat frame to a folded relation.

What is claimed is:

1. A folding chair, including a back frame, a seat frame pivotally connected within the back frame for nesting therein, and front and rear legs pivotally connected to the seat frame within the confines thereof for folding to a nested relation within the seat and back frames.

2. A folding chair, including a back frame, a seat frame pivotally connected within the back frame for nesting therein, front and rear legs pivotally connected to and within the confines of the seat frame for nesting within the seat and back frames, and connections between the legs and back frame, and disposed within the confines thereof for holding the chair in set-up condition. 70

3. A folding chair, including a back frame, a seat frame pivotally connected within the back frame, front and rear legs pivotally connected on the inside of the seat frame for nesting of the seat frame and legs completely within the confines of the back frame 80 when the chair is in folded condition, and connections between the legs and the back frame respectively for holding the chair in set-up condition. 75

4. A folding chair, including a back frame, a seat frame pivotally connected within the back frame, front and rear legs pivotally connected on the inside of the seat frame for nesting of the seat frame and legs completely within the confines of the back frame 90 when the chair is in folded condition, and connections between the legs and the back frame respectively for holding the chair in set-up condition, said connections also nesting within the confines of the back frame 95 when the chair is folded. 85

5. In a folding chair, a back frame, a seat frame pivoted at its rear end within the back frame for folding to a nested position within the confines thereof, and front and rear supporting legs pivoted on aligned axes to the forward inside portion of the seat frame for folding to a nested position partially within the confines of said seat frame and wholly within the confines of the back 100 frame. 105

6. In a folding chair, a back frame, a seat frame pivoted at its rear end within the back frame for folding to a nested position within the confines thereof, front and rear supporting legs pivoted on aligned axes to the forward inside portion of the seat frame for folding to a nested position partially within the confines of said seat frame and wholly within the confines of the back frame, 110 and connections between the lower ends of the back frame and the front and rear legs respectively for supporting and bracing the chair when set up and for effecting movements of the elements in unison. 115

7. In a folding chair, a back frame, a seat frame pivoted at its rear end within the back frame for folding to a nested position within the confines thereof, front and rear supporting legs pivoted on aligned axes to the forward inside portion of the seat frame for folding to a nested position partially within the confines of said seat frame and wholly within the confines of the back frame, and connections between the lower ends of 120 125

- the back frame and the front and rear legs respectively for supporting and bracing the chair when set up, said connections being also foldable together with
- 5 the seat frame and legs to a nested position within the confines of the back frame.
8. In a folding chair, U-shaped back and seat frames, the latter having its free ends pivoted within the former at a point inter-
10 mediate the bight and free ends thereof for folding of the latter to a nested position within the former, front and rear legs pivoted within the seat frame at a point ad-
15 jacent the bight portion for folding to a nested position within the seat frame, said legs being of a length to be disposed within the confines of the back frame, and connec-
20 tions between the free ends of the back frame and the front and rear legs respec-
tively.
9. A folding chair, including an inverted U-shaped back element fabricated of angle iron having inwardly extending rear flanges and forwardly extending side flanges, a U-
25 shaped seat frame fabricated of angle iron having inwardly extending upper flanges and depending side flanges, the free rear ends of the depending side flanges of the seat frame disposed within the side flanges
30 of the back element and pivotally connected therewith for folding movement of the seat frame to a nested position within the con-
fines of the back element, a pair of front and rear legs pivoted on aligned axes and
35 disposed within the depending side flanges of the seat frame adjacent the forward por-
tion thereof for folding movement to a nested position with respect to the seat frame, the said rear legs when the chair is
40 set up extending rearwardly at an angle, and connections respectively between the lower ends of the back element side flanges and the front and rear legs for supporting and bracing the chair when in a set-up condition.
10. A folding chair, including a back frame, a seat frame pivotally connected within the back frame, front and rear legs pivotally connected on the inside of the seat frame for nesting of the seat frame and
45 legs completely within the confines of the back frame when the chair is in folded con-
dition, connections between the legs and the back frame respectively for holding the
50 chair in set-up condition, and means for locking the legs in opened condition to pre-
55 vent accidental collapsing of the chair when set up.
11. In a folding chair, a back frame, a seat frame pivoted at its rear end within
60 the back frame for folding to a nested po-
sition within the confines thereof, front and rear supporting legs pivoted at aligned axes to the forward portion and on the inside of
65 the seat frame for folding to a nested po-
sition partially within the confines of the seat frame and wholly within the confines of the back frame, connections between the lower ends of the back frame and the front and rear legs respectively for supporting
70 and bracing the chair when set up, the front and rear legs having cross braces, and a
75 locking bail pivotally attached to the rear supporting legs and gravitationally engage-
able with the cross brace of the front sup-
porting legs for locking the chair in an opened set-up condition.

Signed at New York in the county of New York and State of New York this 28th day of October, A. D. 1927.
